UNITED STATES PATENT OFFICE.

WILLIAM E. SHRAYER, OF NORWALK, CONNECTICUT.

RAZOR HONING AND STROPPING DEVICE.

Application filed August 10, 1922. Serial No. 580,834.

To all whom it may concern:

Be it known that I, WILLIAM E. SHRAYER, a citizen of the United States, residing at Norwalk, in the county of Fairfield and State of Connecticut, have invented certain new and useful Improvements in Razor Honing and Stropping Devices, of which the following is a specification.

My invention relates to razor honing and stropping devices adapted to sharpen razor blades of all types.

The objects are to provide a razor blade sharpening device whereby no skill is required of the user to hone or strop a razor blade of any type; and to provide a simple and durable device of comparatively few parts in which no part can get out of proper and positive adjustment.

These objects, and other advantageous ends which will be described hereinafter, I attain in the following manner, reference being had to the accompanying drawings in which—

Figure 1 is a side elevation of a device constructed in accordance with my invention,

Figure 2 is a front elevation of Figure 1, having the strop partly broken away;

Figure 3 is a section taken on the line 3—3 of Figure 1,

Figure 4 is a perspective view of a detachable blade gripper,

Figure 5 is a view similar to Figure 1 showing the blade holder adjusted to another position, and

Figure 6 is a section taken on the line 5—5 of Figure 2, showing the blade holder adjusted to a position similar to Figure 5 but showing the blade moved to the opposite side of strop.

The device comprises a frame 1 having mounted, adjacent one end, rotating hones 2 spaced apart. A rocker 3, is mounted near the other end and its ends 4 are connected by rocker pins 5, 6 and 7. A rocker shaft 8, which passes through the ends 4 of the rocker, is secured to frame 1. Strop guide pins 9 and 10 are arranged so that strop 11 is held against the hones 2. The strop 11, which passes over rocker pins 5 and 6, and between hones 2 and guides pins 9 and 10, has handles 12 secured to its ends.

An oscillating holder 13 comprises a member 14 having at each end, a slot 15 to receive the rocker pin 7. A spring clamp 16 is secured to member 14 and receives a

detachable blade gripper 17 adapted to grip a razor blade 18. A shaft 19, on which the holder 13 oscillates, passes through member 14, slots 20 in the frame and springs 22, and has collars 23 fixed at its ends. Thus springs 22, which are preferably made in the form of rings, are positioned between frame 1 and collars 23. Locking pins 24 are secured to springs 22 at such distance from shaft 19 that the pins will abut one end of slots 20 and shaft 19 will abut the other end of the slots. A hook 25 or other means may be employed to hold the device while in use.

When it is desired to hone a razor blade, the blade 18 is placed in detachable blade gripper 17, as shown in Figure 4 and gripper 17 is placed in clamp 16 of holder 13. Handles 12, at the ends of strop 11, are reciprocated alternately. This movement causes blade 18 to engage hones 2 which are rotated by strop 11 held in engagement therewith by guide pins 9 and 10.

To strop the razor blade, the locking pins 24 are pulled out of slots 20 against the action of springs 22, and shaft 19 and locking pins 24 are moved so they will engage the opposite ends of the slots, as clearly shown in Figures 5 and 6. This movement causes razor blade 18 to engage strop 11 when actuated by handles 12.

Thus a razor blade may be honed and stropped without requiring any skill of the user.

By providing a structure with a detachable blade gripper, any type of razor blade may be honed or stropped by using a blade gripper to fit the particular blade.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A honing and stropping device including a frame; hones rotatable in the frame; rocking means mounted in the frame; a strop sliding in the frame and operating the hones and rocking means; blade moving

means adjustable in the frame relatively to the rocking means to bring the blade in position to engage either the hones or strop; means for keeping the rocking means in operative connection with the blade moving means when adjusted to either position, and means for retaining the blade moving means in adjusted position.

2. A honing and stropping device including a frame; hones rotatable in the frame; a rocker mounted in the frame; a strop sliding in the frame and operating the hones and rocker; an oscillating blade holder adjustable in the frame relatively to the rocker to bring the blade in position to engage either the hones or strop; means for keeping the rocker in operative connection with the holder when adjusted to either position, and means for retaining the holder in adjusted position.

3. A honing and stropping device including a frame having slots; hones rotatable in the frame; a rocker mounted in the frame; a strop sliding in the frame and operating the hones and rocker; a shaft adjustably mounted in the slots; an oscillating blade holder mounted on the shaft whereby the shaft may be adjusted to bring the blade in position to engage either the hones or strop; means for keeping the rocker in operative connection with the holder when adjusted to either position, and means for retaining the shaft in adjusted position.

4. A honing and stropping device including a frame having slots; hones rotatable in the frame; a rocker mounted in the frame; a strop sliding in the frame and operating the hones and rocker; an oscillating holder mounted in the slots and adjustably connected to the rocker; springs connected to the holder, and locking pins on the springs adapted to enter the slots and retain the holder in adjusted position.

5. A honing and stropping device includ-

ing a frame having slots; hones rotatable in the frame; a rocker mounted in the frame; a strop sliding in the frame and operating the hones and rocker; a shaft adjustably mounted in the slots; an oscillating holder mounted on the shaft and adjustably connected to the rocker; springs connected to the shaft, and means on the springs adapted to enter the slots to hold the shaft in adjusted position.

6. A honing and stropping device including a frame having slots; hones rotatable in the frame; a rocker mounted in the frame; a strop sliding in the frame and operating the hones and rocker; a shaft adjustably mounted in the slots; an oscillating holder mounted on the shaft and adjustably connected to the rocker; springs connected to the shaft, and locking pins on the springs adapted to enter the slots to hold the shaft in adjusted position.

7. A honing and stropping device comprising a frame having slots; rotating hones mounted adjacent one end of the frame; a rocker mounted adjacent the other end; a strop engaging the hones and rocker; guiding pins for holding the strop in engagement with hones; a shaft adjustably mounted in slots in frame disposed between the hones and rocker; an oscillating holder mounted on the shaft and adjustably connected to the rocker; springs connected to the shaft, and locking pins on the springs adapted to enter the slots and lock the shaft in adjusted positions to cause a blade to engage either the hones or strop.

In testimony whereof I have signed my name to this specification in the presence of two subscribing witnesses.

WILLIAM E. SHRAYER.
